UNITED STATES PATENT OFFICE.

WINFIELD L. FULLER, OF WALKER, KANSAS.

VENTILATED CREMATORIAL-CLOSET.

SPECIFICATION forming part of Letters Patent No. 446,340, dated February 10, 1891.

Application filed April 2, 1890. Serial No. 346,345. (No model.)

To all whom it may concern:

Be it known that I, WINFIELD L. FULLER, of Walker, in the county of Ellis and State of Kansas, have invented certain new and useful Improvements in Ventilated Crematory-Closets; and I do hereby declare that the following is a full, clear, and exact description thereof, reference being had to the accompanying drawing, and to the letters of reference marked thereon, which form part of this specification, in which the figure represents a vertical sectional view of my improved dry-closet or apparatus for burning refuse, excretory, or fecal matter.

This invention is an improvement in apparatus for receiving and destroying or burning excretory matters in dwelling-houses, and its object is to provide an odorless or gas-tight receptacle wherein the fecal matters can be collected and burned and the infectious noxious gases generated therefrom be destroyed or conducted off where their discharge cannot injuriously affect the residents of the dwelling, and the escape of such gases therein be prevented. It is also designed to separate the solid and fluid matters and conduct the latter out of the receptacle to a proper subterranean drain or outlet. These objects I accomplish by the apparatus illustrated in the drawing, and hereinafter described and claimed.

In the figure of the drawing is represented a furnace and receptacle combined, and preferably built up in sections.

A designates the lowermost section, preferably annular in transverse section, and mounted on feet or other proper supports, and forming the ash-pit, having a door *a* at one side.

B designates the fire-box section superimposed on section A and provided with an ordinary grate and a door *b* at one side.

C designates a third section of less diameter than section B, having a bottom *c* extending beyond the sides thereof sufficiently to rest upon the top edges of section B and sustain section C thereon. This section C forms the lower portion of the fecal-matter receptacle of the apparatus and the top of the fire-chamber. It has an opening *C'* at one side, closed by a sealed cover *c'*, of convenient construc-

tion. Superimposed on section C may be other annular sections, two D D being illustrated in the drawing, according to the depth and size of fecal receptacle desired. These sections of the receptacle are or may be united by flange and bead joints, as illustrated, or otherwise, provided tight joints are insured.

E designates the top of the receptacle, conical in form and fitted tightly over the upper section D, closing the same. Its edges project beyond the section D, however, and are jointed also to the upper edge of a metallic casing or shell F, surrounding the receptacle, and united at bottom to the upper edge of section B. The space between shell F and the receptacle forms a draft chamber or flue communicating at bottom with the fire-chamber through an opening *f* in part C, as shown, and at top with a pipe G, leading to a chimney or flue. The casing has a door therein opposite door C' in the receptacle.

H designates a pipe extending through sections A B into the bottom of section C. This pipe, communicates at bottom with a drain-pipe, by which fluids will be conducted off, or it can be extended several feet into and below the ground and then packed with cement above its outlet to prevent rising of noxious vapors. Only fluids are carried off through said pipe, and its upper end is provided with a sieve *h*, to prevent solid matters entering therein.

e is an inwardly-projecting drain-flange on top E, which conducts the water of condensation deposited from vapors rising in the receptacle to a point at one side thereof and delivers them into the mouth of a tube I, which extends downward into pipe H, as shown. The object is to separate fluids from the solid matters in the receptacle.

J designates the soil-pipe communicating with the receptacle through an opening in one side of top E, as shown. The lower end thereof has an inner channel or bead *j*, the lowest point of which is directly above the mouth of tube I. In this channel the moisture and water descending the sides of the soil-pipe are caught and conducted into tube I, while solid matters descend into the receptacle. A bed of charcoal is kept in the receptacle, upon which the solid matters are de-

posited. The soil-pipe is preferably set vertical, and at its upper end is connected to a commode or privy seat.

K designates a vent-pipe leading from the upper section D into the draft-pipe G, and L is a gas-conducting pipe connected to pipe K outside the receptacle and extending down between the walls thereof and the casing into the fire-chamber, and adapted to conduct gases into or above the fire in said chamber. Pipe L may be disconnected from pipe K when there is no fire in the chamber B, and pipe K be closed by a cap over the flange by which pipe L is usually connected thereto, access being had for this purpose through an opening in casing F, closed by a door M. A shelf N is fixed in the casing near pipe G, on which a lamp can be placed when there is no fire in the furnace for the purpose of creating an artificial draft in pipe G. The end of pipe K within pipe G has a bell-mouth k, and in front thereof is a conical deflector O, secured within the pipe. When there is an upward draft through pipe G, this cone and bell-mouth act as an ejector to draw gases from the fecal receptacle; but if there should be any back draft by accident through pipe G the cone deflects the draft out of pipe K into the space between the casing and receptacle, so that poisonous gases will not be driven back into the receptacle and thence into the soil-pipe or building. The matters deposited on the bed of charcoal accumulate until the receptacle is sufficiently charged to require cleaning. This can be ascertained by peep-openings, or known by the size of the apparatus, the number of persons using the same, and the length of time of its use. The urine and other fluids descending the soil-pipe are drained off into pipe H, and should any fall into the bed in the receptacle they will be leached by the charcoal, which absorbs poisonous gases. At proper intervals a fire is kindled in the fire-chamber and kept going until the charcoal and matter in the receptacle have been reduced to ashes. The charcoal materially assists in facilitating the combustion of the matters. The resultant ashes can be removed and a fresh supply of charcoal introduced into the receptacle.

The apparatus can be used even while the fire is burning, as the gases are sucked out of the receptacle and the draft in pipe G creates a downward current through the soil-pipe if opened or uncovered. Preferably pipe G leads into the common house-flue. By using pipe L much of the gas evolved in the receptacle can be drawn into the fire-chamber and consumed.

Having thus described my invention, I claim—

1. A furnace for burning refuse matters, comprising a fire-chamber section, a fecal-matter receptacle built up of cast-metal rings, and a cover closing the top thereof, the soil-pipe entering the receptacle through said cover, a tight casing inclosing said receptacle and forming a cylindrical flue leading from the combustion-chamber, the flue-pipe communicating with said casing, and the short pipe entering said flue-pipe and communicating with the fecal-matter receptacle, all substantially as set forth. 65

2. A furnace for burning fecal matters, consisting of a fire-chamber, a fecal-matter receptacle superimposed on the fire-chamber, but not communicating therewith, a soil-pipe entering the top of said receptacle, and a drain-pipe leading therefrom, in combination with a metallic casing inclosing the fecal-matter receptacle and supported on the fire-chamber section, the flue-pipe connected therewith, the pipe leading from said receptacle into the flue-pipe, and the drain-pipe and drip-pipe, all substantially as specified. 75

3. The combination of the fecal-matter receptacle having a conical top interiorly flanged to form a drain for water of condensation, a drain-pipe for fluids only leading from said receptacle, the tube conducting water of condensation from the top into said drain-pipe, and the soil-pipe connected with said receptacle, all substantially as set forth. 80

4. The combination of the fecal-matter receptacle having a conical top flanged on its inner side to form a drain, with the soil-pipe entering said top, having its lower end channeled, and the tube for conducting water from said drain and channel into a drain-pipe, substantially as specified. 95

5. The combination of the ash-pit and fire-chamber sections, the sections superimposed thereon, forming the fecal-matter receptacle, and the conical top closing said receptacle, having a flange on its under surface forming a drain for water of condensation, and the soil-pipe entering said top, and the fluid-draining tubes and pipes, with the casing inclosing said receptacle and communicating with the fire-chamber, a draft-pipe leading from said casing, and a vent-pipe leading from the receptacle into the draft-pipe, having a bell-mouth, and a conical deflector in the draft-tube, all constructed and arranged substantially as and for the purpose specified. 105

In testimony that I claim the foregoing as my own I affix my signature in presence of two witnesses.

WINFIELD L. FULLER.
